No. 831,295.

PATENTED SEPT. 18, 1906.

W. H. PONTIUS.
SHIELD FOR CAR HANDLES.
APPLICATION FILED MAY 28, 1906.

UNITED STATES PATENT OFFICE.

WILLIAM H. PONTIUS, OF COLUMBUS, OHIO.

SHIELD FOR CAR-HANDLES.

No. 831,295.

Specification of Letters Patent.

Patented Sept. 18, 1906.

Application filed May 28, 1906. Serial No. 319,048.

To all whom it may concern:

Be it known that I, WILLIAM H. PONTIUS, a citizen of the United States, residing at Columbus, in the county of Franklin and 5 State of Ohio, have invented certain new and useful Improvements in Shields for Car-Handles, of which the following is a specification.

My invention relates to a shield for car-handles, and has for its object the provision of a shield arranged in such manner upon the side posts of open or summer cars as to prevent the handle upon said side posts from being grasped by persons who occupy the 10 seat in front of said handle, while leaving said handle accessible to persons who occupy seats in the rear thereof, thus requiring persons alighting from said cars to face the front thereof.

15 It is a well-known fact that many accidents are caused by people facing the rear of the car when alighting, and the present invention is designed to provide simple and efficient means for preventing some, if not 20 all, of these accidents.

In the accompanying drawings, Figure 1 is a side elevation of a portion of a summer-car, illustrating my invention applied thereto, and Fig. 2 is a horizontal section upon line 30 *xx* of Fig. 1.

Like numerals designate corresponding parts in both of the figures of the drawings.

Referring to the drawings, the numeral 5 designates the car-floor, and the numerals 6 35 designate adjacent seats in said car. The usual swinging backs 7 are carried by brackets 8, said brackets being pivoted in the usual and well-known manner to the side posts 9. The usual handles 10 are secured to these 40 side posts.

So far the parts described are all of the well-known construction such as may be found upon most of the street-cars now in use.

45 In carrying out my invention I secure shields 12 in front of the handles 10 by means of fastening devices 13. By referring to Fig. 2 it may be seen that the shields 12 are arranged upon opposite sides of the 50 handles upon opposite sides of the car. The reason for thus arranging these shields is that by so doing it is unnecessary to have shields which may be shifted from one side

of the handle to the other, but a plain metallic shield immovably mounted may be 55 used. Passengers are always required to alight upon the right-hand side of the car. It follows, therefore, that when the car is going in the direction of the arrow *a*, the shields shown at the upper side of Fig. 2 are 60 upon the right-hand side of the car and are consequently in proper position to serve the objects of the present invention, while when the car is going in the direction of the arrow *c* the shields at the lower portion of Fig. 2 65 are upon the right-hand side of the car and likewise serve said purpose.

From the foregoing description it will be seen that simple and efficient means are herein provided for accomplishing the objects of 70 the invention; but while the elements herein shown and described are well adapted to serve the purposes for which they are intended, it is to be understood that the invention is not limited to the precise construction set forth, but includes within its purview such changes as may be made within 75 the scope of the appended claims.

What I claim is—

1. The combination with a car-handle, of 80 an immovable shield secured in position in front of said handle.

2. The combination with a car-handle and its supporting-post, of an immovable shield secured to said post in such position as to 85 prevent said handle being grasped from the front of said post.

3. The combination with the car-handles arranged upon opposite sides of open cars, of shields arranged in front of said handles, 90 said shields being arranged at the front sides of said handles upon each side of said car.

4. The combination with a plurality of car-handles and their supporting-posts, of a plurality of shields arranged upon each side 95 of the car, the shields upon one side of the car lying upon the opposite side of the handles from the shields upon the other side of the car.

In testimony whereof I affix my signature 100 in presence of two witnesses.

WILLIAM H. PONTIUS.
